UNITED STATES PATENT OFFICE.

JOHN A. CLOUGH, OF SPRING VALLEY, WISCONSIN.

STEP-LADDER.

No. 923,246.

Specification of Letters Patent.

Patented June 1, 1909.

Application filed June 29, 1908. Serial No. 440,794.

To all whom it may concern:

Be it known that I, JOHN A. CLOUGH, a citizen of the United States, residing at Spring Valley, in the county of Pierce and 5 State of Wisconsin, have invented certain new and useful Improvements in Step-Ladders, of which the following is a specification.

My invention relates to improvements in step ladders, its object being particularly to 10 provide improved means for supporting the legs of a step ladder in adjusted positions.

To this end my invention consists in the features of construction and combination hereinafter particularly described and claimed.

15 In the accompanying drawings forming part of this specification, Figure 1 is a perspective view of a step ladder embodying my invention, Fig. 2 is a view of a portion of one of the supporting legs of the ladder showing 20 one side of a collar forming part of my invention, Fig. 3 is a similar view of the inner side of the other leg showing the other side of the collar, Fig. 4 is an end view of one of the legs, and Fig. 5 is a detail of a bent bar forming 25 part of my invention.

In the drawings A represents a step ladder of ordinary construction, the rear legs 3 being formed along their inner sides with a plurality of notches 2.

30 C represents a bail having hinge connection 3 with the front portion of the ladder and having pivotal support 4 in the rearwardly extending ears 5 of a pair of collars D slidable upon the legs 3. The collars D are 35 held in adjusted positions upon the legs by means of bent bars 6 slidable in guides 7 and 8 on the sides of the collars, each of said bars being held in indrawn position by a spring 9 connected at one end to the bar and at the 40 other end with an ear 10 carried by the collar. The spring 9 is centrally held by a notched catch 11 extending outwardly from the adjacent side of the collar. One side of

the bar extends rearwardly beyond the collar to form a finger hold 12 to allow the bars 45 to be pressed out of the receiving notches 2 when adjusting said collars upon the legs.

In operation the bent bars 6 will be held in corresponding notches 2 by the springs 9 holding the ladder legs in position. When 50 it is desired to adjust the ladder legs the bent bars may be forced out of the notches and the collars adjusted upon the supporting legs to carry said legs to the desired position.

I claim:

1. In combination with the side standards and supporting legs of a step ladder, collars slidable upon said supporting legs, a bail hinged upon said side standards and having hinge connection with said collars, and 60 spring held means carried by said collars and coöperating with said legs to hold said collars in adjusted positions thereon.

2. In combination with the side standards and supporting legs of a step ladder, said 65 supporting legs being formed with a series of transverse notches, collars slidable upon said legs, a connection between said collars and standards and a spring pressed locking device carried by said collars in position to co- 70 operate with said notches.

3. In combination with the side bars and supporting legs of a ladder, said supporting legs being formed with transverse notches, of collars slidable upon said legs, a connection between said collars and standards, and spring pressed bars slidably supported upon 75 said collars in position to coöperate with said notches.

In testimony whereof I affix my signature 80 in presence of two witnesses.

JOHN A. CLOUGH.
